UNITED STATES PATENT OFFICE.

GILBERT C. CAMPBELL, OF HUMPHREYS, MISSOURI.

DISPLAY-CABINET.

1,287,216.

Specification of Letters Patent. Patented Dec. 10, 1918.

Application filed December 27, 1916. Serial No. 139,174.

To all whom it may concern:

Be it known that I, GILBERT C. CAMPBELL, citizen of the United States, residing at Humphreys, in the county of Sullivan and State of Missouri, have invented certain new and useful Improvements in Display-Cabinets, of which the following is a specification.

This invention relates to cabinets and particularly to what are known as display cabinets such as are used by retail merchants to hold and exhibit ready made clothing, the cabinet serving to protect the clothing from dust and destructive insects, and being provided with glass doors the contents may be readily seen by customers. The cabinet is also provided with means adapted to be withdrawn when the doors are open for the easy access of the salesman to the goods exhibited within the cabinet.

Another object of the invention is to provide a cabinet made of parts that may be readily put together by means of screws and which can be packed in small compass for transportation.

A further object of the invention is to provide a display cabinet having a sliding panel carrying a mirror for the convenience of customers which, when not in use will slide into a suitable recess in the cabinet so as to be wholly out of the way and protected from breakage but which may be quickly withdrawn when desired for use. Furthermore these cabinets can be made in single or double units the former to be placed against the wall of a room while the latter of double width are so placed that they may be approached from both sides and therefore are provided with doors on each of said sides.

With these as the principal objects in view the invention consists of the novel construction, combination and arrangement of parts hereinafter described, pointed out in the claims and illustrated in the accompanying drawings, in which—

Figure 1 is a perspective view of the complete cabinet as it appears when in use, Fig. 2 is a vertical longitudinal sectional view through the cabinet,

Fig. 3 is a vertical transverse sectional view on the line 3—3 of Fig. 2,

Fig. 4 is a similar sectional view on the line 4—4 of Fig. 2,

Fig. 5 is a horizontal sectional view on the line 5—5 of Fig. 2,

Fig. 6 is a perspective view of a slide and its support from which goods for exhibition or sale are hung and by means of which they may be withdrawn from the cabinet,

Fig. 7 is a cross sectional view of the same parts,

Fig. 8 is a cross sectional view of a portion of the cabinet showing the manner of mounting the sliding doors on anti-friction bearings,

Fig. 9 is a detail perspective view showing a feature of the invention, and

Figs. 10 and 11 are sectional detail views of other detail structures.

In the drawings it will be seen that the cabinet comprises a bottom 15 that rests upon the floor, a top 16, paneled ends 17 and 18, a back 19 and a front formed by the doors 20 and 21, and a base strip 22 having openings for a plurality of drawers 23.

The bottom 15 is preferably made double as shown in Figs. 2, 3 and 4 the top and bottom floors of this bottom being separated by cross strips 24 to which the floors are fastened and by means of which they are held at a proper distance apart and securely framed together. The top 16 is also made double and securely framed to cross strips 25. The front and sides of this top are finished with a molding 26, while a footing 27 is placed around the bottom 15.

The ends 17 and 18 of the cabinet extend upwardly from the bottom 15 to the top 16 and are secured to said parts by screws or other removable fastenings. These side pieces are like the top and bottom made of wood and as shown in Fig. 1 each of the sides is paneled to render the cabinet more ornamental. The back 19 of the cabinet also extends from the bottom to the top and may be made plain or paneled as circumstances call for. The back is joined to the bottom and top by screws and at the corners of the cabinet between the back and the two sides are vertical strips 28 to which said back and sides are screwed and which securely join said parts.

The drawers 23 which may be large or small as the needs of the cabinet demand, slide upon the bottom 15 into and out of the cabinet through openings in the base strip 22. Suitable drawer pulls 29 being provided on the front of the drawers for 110

moving the same. Guide strips 30 fastened on the bottom 15 of the cabinet within the same direct the movement of the drawers.

At a convenient height above the top of the drawers 23 is a horizontal partition 31 that separates the lower or drawer compartment 32 from the upper open or display compartment 33. This partition extends from the back to the front of the cabinet and between the ends 17 and 18, inverted right angled guide bars being secured on the upper side of the partition adjacent the ends 17 and 18. Between the guide bars 34 in the center of the casing is a third 15 guide bar 35 of T shape which in connection with the guide bars 34 provide sliding means for two horizontal platforms or boards 36 that may be withdrawn from the cabinet when the doors 20 and 21 are open 20 thus bringing into convenient position for exhibition and handling the goods resting upon said platforms. Rollers 37 are secured on the under side of the platforms 36 and travel over the top of the partition 31 thus 25 reducing the friction of said platforms and permitting their easy withdrawal from the cabinet.

The doors 20 and 21 are each formed of a rectangular frame 39 filled in with a glass 30 panel 38 through which the goods or articles in the cabinet may be viewed by customers. Each door is provided with a handle 40 by means of which the cabinet may be opened by sliding one or the other of the doors in a 35 horizontal direction, they being mounted in grooves 41 and 42 formed in the top of the partition 31 and similar grooves in a strip 43 just below the molding 26 of the top 16. The doors 20 and 21 are mounted on balls 44 40 that run in grooved metal strips 45 seated in the bottom of the grooves 41 and 42 and similar metal strips on the bottom of the door frames. The doors slide toward the ends of the cabinet in parallel planes, the 45 inner edges of the doors overlapping when the cabinet is closed.

Fastened to the top 16 of the cabinet and within the same are a number of spaced parallel bars 46 that support and guide 50 slides 47 which when the doors are open may be withdrawn from the cabinet. The guide bars 46 have their sides inclined in opposite directions as shown in Figs. 6 and 7, these inclined sides facing when the bars 55 46 are screwed in place and form thereby a series of channels extending from end to end of the top across the same. The channels are wider at the top than at the bottom and serve as runways for the slides 47 60 which are also made wider at their top sides and shaped to fit said runways. There is a longitudinal groove 48 formed in the top of each slide 47 to receive a stop pin 49 that limits the outward movement of the slide. 65 Screwed into the bottom of each slide 47

is a screw eye 50 or other means fastened thereto upon which a coat hanger may be hung, the number of slides 47 depending upon the length of the cabinet, sixteen being shown in the drawings, eight behind each door, thus enabling any one or all of each eight to be readily withdrawn when the door in front thereof is opened.

Close to the cabinet end 18 and extending upwardly from the partition 31 to the top 75 of the cabinet is a vertical partition 51 that forms a recess to receive a mirror 52 mounted in a rectangular frame 53 slidable on rollers 54 at the bottom of the recess. The mirror passes through a long vertical 80 slot in the front of the casing as shown in Fig. 1 and when in closed position the end of the mirror frame lies flush with said front. A hand grip 55 is fastened to the mirror for withdrawing the same from the recess. 85

A cabinet such as described is of great convenience for the displaying of ready made clothing as coats and vests or coats alone may be carried by hangers and suspended from the screw eyes 50. Trouser 90 or trousers and vests properly folded will be carried on the platforms 36 while if desired fancy vests or other articles may be placed in the drawers 29. When a sale is to be made one of the doors 20 or 21 will 95 be moved to one side thus opening the cabinet and permitting the clerk to withdraw a slide 47 and bring into convenient position for removal the particular coat supported on that slide. When a selection has 100 been made, the platform 36 of the same side can then be drawn out and the trousers and vest removed. Upon completing the sale, the slides 47 and platform 36 are returned to the cabinet and the door closed. The 105 goods within the cabinet are, by this manner of exhibiting them, preserved from undue handling and disarrangement whereby they become creased and more or less out of shape whereas placing them in a cabinet 110 such as described they are protected and the appearance of the store is improved, made more attractive to customers and increases the business of the merchant.

What I claim is:

1. A cabinet comprising a base, a top, two sides, and a back secured together for ready disassembling, a horizontal partition near the base dividing the cabinet into upper and lower compartments, horizontal 120 platforms slidable on said partition into and out of the upper compartment, a plurality of guide bars secured in spaced parallel relation to the top of the cabinet and within the same, said guide bars having 125 inclined sides and being wider at the bottom than at the top, bars having inclined sides and wider at the top than at the bottom and slidable between said guide bars into and out of the upper compartment, suspend- 130

- ing means on said slides, and sliding doors for closing the front of the upper compartment.
2. In a display cabinet having top and bottom sides and doors by means of which latter ready access may be had to the cabinet, a plurality of sliding bars movable into and out of the cabinet for supporting articles to be displayed, said bars having oppositely inclined sides and being wider at the top than at the bottom, means secured to the underside of the bars from which articles displayed may be suspended, guides for said slides comprising a plurality of bars having oppositely inclined slides and wider at the
- 10
- 15

bottom than at the top secured in parallel relation to the top of the casing and spaced apart a distance to permit easy movement of the slides therebetween, but close enough to prevent the slides falling therefrom, and 20 platforms on the bottom of the cabinet adapted to be moved into and out of the same upon which platforms articles for display may be placed.

In testimony whereof I affix my signature 25
in presence of two witnesses.

GILBERT C. CAMPBELL.
